UNITED STATES PATENT OFFICE

2,475,695

GAME COUNTER

Gertrude S. Castner, Detroit, Mich.

Application December 19, 1947, Serial No. 792,704

1. Claim. (Cl. 235—127)

This invention relates to tally devices for use in playing games of cards, and more particularly to a tally or score board device for use in playing pinochle.

A main object of the invention is to provide a novel and improved pinochle scoring device which is very simple in construction, easy to operate, and which enables a player to keep an accurate record of his original bid, points melded and points earned in subsequent play, whereby his total score may be readily computed.

A further object of the invention is to provide an improved scoring device for pinochle which provides a means of temporarily recording a player's bid and points melded so that by adding to the points melded the points earned during subsequent play, the player's total score may be readily computed and compared with the points bid, the device being inexpensive to manufacture, sturdy in construction, and contributing to the enjoyment of the game by providing a player with a reminder of his point standing after he has taken a bid and engages in subsequent play.

Further objects and advantages of the invention will become apparent from the following description and claim, and from the accompanying drawings, wherein:

Figure 1 is a top plan view of a pinochle scoring device constructed in accordance with the present invention.

Figure 2 is an enlarged fragmentary perspective view of one of the scoring device of Figure 1, showing a scoring tab in upright position.

Figure 3 is a transverse vertical cross-sectional view taken on line 3—3 of Figure 2.

Figure 4 is an enlarged detail perspective view of a scoring tab employed in the scoring device of Figure 1.

Figure 5 is an enlarged detail perspective view of one of the leaf springs employed with the scoring tabs in the scoring tabs in the scoring device of Figure 1.

Referring to the drawings, 11 designates a flat generally rectangular housing made of suitable material, such as sheet metal or plastic, said housing having a top wall 12 which is divided into four sections by transverse lines 13 suitably inscribed on said top wall. The aforesaid sections are respectively marked "Bid," "Meld," "Points" and "Total score," as shown in Figure 1.

Formed in top wall 12 and extending in opposing transverse relation to each other for the length of said top wall are two longitudinal rows of rectangular apertures 14. Secured to the

underside of top wall 12 beneath the respective rows of apertures 14 are respective longitudinally extending wires 15, 15, said wires being secured at their ends to the underside of said top wall 12, as shown at 16, 16 and 17, 17, being further secured at their intermediate portions to the underside of said top wall subadjacent to the division line markings 13, as shown at 18.

Designated at 19 are scoring tab elements, each tab element comprising of an elongated flat body portion 20 and a right angled end portion 21, apertured parallel lugs 22, 22 being provided at the corner junction between body portion 20 and end portion 21. Each tab element 19 is pivotally secured to a wire 15 in an aperture 14, as shown in Figure 3, the wire 15 passing through the apertured lugs 22, 22 of the tab elements.

Secured to the underside of top wall 12 between each transversely opposed pair of apertures 14, by a center rivet 23, is a transversely extending leaf spring 24. The ends of leaf spring 24 are formed with right-angled depending seat elements 25, 25 underlying the angled end portions 21 of the tab elements in said pair of opposed apertures 14. As shown in Figure 3, when the body of a tab element is in a horizontal position its end portion 21 is vertical and abuts the vertical wall defined at the inner end of its associated seat element 25, whereby the spring 24 resiliently locks the tab element in the horizontal position shown at the left side of Figure 3. When the body of a tab element is rotated upwardly to a vertical position, as shown at the right side of Figure 3, the corner at the junction between the body 20 and the end portion 21 of the tab element interlocks with the right-angled seat element 25 associated therewith, whereby the tab element is resiliently locked in a vertical position.

As shown in Figures 1 to 3, the free ends of the tab elements 19 normally project beyond the longitudinal side walls of housing 11, thereby facilitating manual actuation of the tab elements from their horizontal to their vertical positions.

Each tab element 19 is marked with suitable indicia so that by raising the appropriate tab elements 19 in the different divisions of the board, arithmetic totals may be represented conforming with an associated game situation. Thus, if a player makes a bid of 310, the first tab element 19 on the left side and the last tab element 19 on the right side in the "Bid" division of the board are raised to vertical positions. If he then proceeds to meld 160 points, the last tab element 19 on the left side and the fourth tab

element 19 on the right side in the "Meld" division are raised to vertical positions. If in subsequent play he proceeds to earn 160 points, the last tab element 19 on the left side and the fourth tab element 19 on the right side in the "Points" division are raised. The player's total score, 320, is then found by adding the amounts represented by the raised tab elements in the "Meld" and "Points" divisions. This total score may be represented in the "Total score" division by raising, for example, the last "20" tab on the left side and the first three "100" tabs on the right side in the "Total score" division. By then comparing the amount of points shown in the "Total score" division with the points bid, shown by the upstanding tabs in the "Bid" section, it can be readily determined that the player has made good his bid with a surplus of ten points.

It is thus seen that a player may readily record his bid in the "Bid" division by raising the appropriate tabs 19 therein, and in the same manner, record his meld in the "Meld" division. After playing out his hand he records his earned points in the "Points" division. He adds his "Meld" and "Points" sums to obtain his total score which he records by raising the appropriate tabs 19 in the "Total score" division. It is then possible to determine at a glance whether or not he has made good his original bid.

If the player does not make the score required and his total score is "minus," the deficiency may be recorded in the "Total score" section and the board reversed until the player is "clear" again.

While a specific embodiment of a pinochle scoring device has been disclosed in the foregoing description, it will be understood that various

modifications within the spirit of the invention may occur to those skilled in the art. Therefore, it is intended that no limitations be placed on the invention except as defined by the scope of the appended claim.

5 What is claimed is:

In a game scoring device comprising a hollow, rectangular body constituting a score board, a plurality of numbered tab elements pivotally secured to said board and arranged in two opposed rows disposed one row along each longitudinal edge of the upper side of said board for individual movement between a position in which they rest upon the upper surface of the board and 10 a position in which they extend upwardly from the board substantially perpendicular to the latter, and respective transverse leaf springs each secured to the board between the two opposing tab elements in said two rows, the arrangement 15 wherein each of said tab elements is formed with a right-angled projection at its pivoted end, and each of said springs is formed at its ends with right-angled seat portions frictionally engaging the rightangled projections on the associated tabs 20 to positively lock said tabs in either of their operative positions.
